United States Patent Office

Des. 218,069

Patented July 14, 1970

218,069

FROZEN BEVERAGE DISPENSER OR SIMILAR ARTICLE

Richard T. Cornelius, Minneapolis, and Clark L. Lofgren, Golden Valley, Minn., assignors to The Cornelius Company, Anoka, Minn., a corporation of Minnesota

Filed Dec. 3, 1968, Ser. No. 14,768

Term of patent 14 years

Int. Cl. D20—01

U.S. Cl. D52—3

FIG. 1 is a perspective view showing the front and one side of a frozen beverage dispenser showing our new design, the opposite side having a similar appearance.

FIG. 2 is a perspective view showing the rear and said one side thereof.

FIG. 3 is a top view thereof.

We claim:

The ornamental design for a frozen beverage dispenser or similar article, substantially as shown and described.
